CLAIM

The ornamental design for a cartridge tape subsystem, as shown and described.

DESCRIPTION

FIG. 1 is a front elevational view of a cartridge tape subsystem showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front, right side perspective view thereof on a slightly reduced scale.
